United States Patent

Des. 241,504
Patented Sept. 21, 1976

241,504

SHARPENING IMPLEMENT

Kurt Krusche, Frankfurt am Main, and Hubert Zimmermann, Seeheim, Germany, assignors to Allstar Verbrauchsguter GmbH & Co. KG, Frankfurt am Main, Germany

Filed Oct. 30, 1975, Ser. No. 627,382

Term of patent 14 years

Int. Cl. D8—05

U.S. Cl. D8—93

FIG.1

FIG.2

FIG.3

FIG.4

FIG.5

FIG.6

FIG.7

FIG. 1 is a front perspective view of a sharpening implement of our new design;

FIG. 2 is a back perspective view thereof;

FIG. 3 is a top view thereof;

FIG. 4 is a bottom view thereof;

FIG. 5 is one end view thereof;

FIG. 6 is the opposite end view; and

FIG. 7 is similar to FIG. 1, showing a variation of the design.

We claim:

The ornamental design for a sharpening implement, as shown and described.
